UNITED STATES PATENT OFFICE.

CLOUD CLIFFORD CONKLING, OF BUFFALO, NEW YORK, ASSIGNOR TO LACKAWANNA STEEL COMPANY, OF NEW YORK, N. Y.

COMPOSITE PILING.

900,343.

Specification of Letters Patent. Patented Sept. 6, 1910.

Application filed April 16, 1909. Serial No. 490,307.

To all whom it may concern:

Be it known that I, Cloud C. CONKLING, a citizen of the United States, residing at Buffalo, in the county of Erie and State of New York, have invented new and useful Improvements in Composite Piling, of which the following is a specification.

My invention relates to interlocking steel sheet piling and consists in new forms of such piling and in the combination therewith of a concrete facing, whereby the piling is made useful for permanent structures.

Of late years interlocking steel sheet piling has come largely into use, and has displaced wooden sheet piling in many locations and for many purposes. This steel sheet piling consists of similarly formed sections having on both edges of the web interlocking flanges, or other interlocking parts, either formed integrally with the web in rolling or secured in position by rivets, whereby, when driving, the sections interlock, each with the adjacent sections on both sides, forming a self sustaining, strong wall. Owing to the increased cost of wood and the improvements in the manufacture of steel, the use and manufacture of this steel piling has been stimulated and important improvements have been introduced, but such piling heretofore has been particularly adapted for temporary use only.

My invention has for its object to adapt this interlocking steel piling to permanent use, and to that end I have devised a special form of such piling and means for protecting it against corrosion by dampness, liquids, gases, etc. The essential features of the invention are the addition of longitudinal ribs to the section webs, provided with rods or other projections, and of a protecting coating of concrete of suitable composition and thickness applied to the sections and firmly bound thereto by engagement with the projections. Such new piling thus consists of a steel core wall which is interlocking and self-sustaining and of a protecting covering of plastic material for the steel core, which also improves the appearance. The new article so produced is practically indestructible and is adapted for use in permanent structures of many kinds.

The main strength of the wall against all strains and forces is afforded by the steel; the concrete is particularly protective in function and renders the wall practically

water tight. In certain locations the concrete also acts as a cushion protecting the steel against the impact of foreign bodies, such as ice, logs, vessels, etc. Such sections and such a wall is essentially different from so-called reinforced concrete structures in this, that in the latter the concrete is the important supporting element, but having its tensile strength increased by metallic bars, rods, wires etc. whereas in my invention the concrete adds as aforesaid little if anything to the strength of the wall, but is of importance for protection, for rendering the wall water-tight and for the sake of appearance.

My invention is particularly adapted for marine work such as revetments, piers, levees, docks, bulk-heads, and dikes, also retaining walls, etc., but I do not propose to limit myself to such uses, for my peculiar pile structure could be used for other purposes, such as the lining of mine shafts or coffer-dams for building foundations, etc. Nor do I propose to limit myself to any particular form of steel piling, for various sorts may be used either rolled or fabricated, the essentials being that the walls shall be interlocking and self sustaining, by the operation of the metallic parts alone, which must be provided with reinforcing ribs and binding projections, for coöperating with the protected covering of plastic material. I have spoken of the interlocking core wall as being made of similar sections, but such wall may be made of dissimilar sections commonly alternately arranged.

I prefer to practice my invention by forming unitary slabs of a single steel section, or at most of two or three steel sections assembled as one, coated with concrete. These slabs, or composite sections, are driven or jetted into place, interlocking as driven, so that the wall is practically finished as the sections are installed. The edges of the slabs are formed to leave pockets finally to be grouted, whereby the grouting is locked in place to form a continuous protective facing and a water-tight wall.

My invention is clearly shown in the drawing herewith in which the reference letters of this description are used to indicate the corresponding parts in all the figures.

More completely to describe and explain the uses and advantages of my invention I

have shown various uses of my peculiar sections in various structures formed therefrom.

Figure 1 shows in plan a portion of a wall built up of my peculiar slabs or composite sections. Figs. 2, 3 and 4 show in plan composite slabs formed respectively with one two or three steel sections, and also certain variations in details of construction. Fig. 5 is a side elevation with portions broken away, of a wall composed of my peculiar slabs or sections. Fig. 6 is the edge elevation of a slab. Fig. 7 is a slight modification of Fig. 6. Fig. 8 is a plan showing a modification in the form of the projections for binding the cement in place. The following figures make plain the characteristic features of my invention and illustrate more particularly the adaptability of my peculiar sections to use in various structures. Fig. 9 is a view in plan showing a series of baffle walls in place to prevent erosion of the shore or bank. Fig. 10 is a plan showing the use of my piling to form a dock or sea wall. Fig. 11 is a plan illustrating a desirable construction for the intersection of two walls. Fig. 12 shows in plan a modification of the structure shown in Fig. 10. Fig. 13 shows a different form of interlocking steel section that may be used in my invention. Fig. 14 shows what I consider to be a most desirable form of steel sheet piling to be used in this and in other connections. Fig. 15 shows a modification in the form of the ribs or concrete binding projections.

Referring more particularly to Figs. 1 to 7 inclusive, 1 indicates a slab or single composite section, provided with any suitable interlocking means along both edges of the web of the steel core for instance flanges 2-2 and 3-3. I have here illustrated what is known to the trade as a double interlocking pile section of the "Lackawanna" type. These sections should be provided with longitudinal stiffening ribs 4 which have the effect greatly to strengthen the steel section against all strains, but are particularly adapted to receive rods, or other projections, for securing the concrete firmly in position. As shown in Fig. 4 more or less straight rods 7 may be provided for this purpose inserted through holes drilled, or punched, in the outer edges of the ribs and conveniently spaced to give sufficient binding strength to the structure in question. The spacing may also be varied in proportion to the thickness and therefore to the weight of the concrete to be applied in different constructions.

As shown in Fig. 3, the rods may be short and inserted through a single rib, but I prefer the form shown in Fig. 4 where the rods are inserted through several ribs of adjacent steel sections and are bent at the ends 8 or

otherwise to maintain them in position particularly during the construction of the slab.

In Figs. 1 and 2 is shown a form of securing rod 9 particularly adapted for a thick covering of concrete. Here the rods are short and inserted through a single rib but are bent outwardly and then inwardly at 10 with their ends 11 engaging with the web, thus giving a spring bearing.

It will be understood that the ribs not only afford a means for attaching the rods, but give a greater adhesive area for the cement which might be sufficient of itself under some conditions to retain the concrete in position, but I prefer to add rods or other projections as shown. Merely for sustaining the binding rods or other projections, the ribs might be non-continuous as shown in Fig. 15, but I prefer continuous ribs as they add greatly to the strength of the wall.

The slabs preferably have their edges provided with longitudinal cavities, as shown, or of other suitable form, to form the pockets 12, when assembled. These cavities leave the contact edges 13, and as these contact edges are narrow friction in driving is reduced and easy driving is promoted. When the slabs are in position these pockets, as well as the joint pockets 15 between the interlocking flanges, are filled with a suitable grout, making a continuous wall with a continuous facing.

Grout in the pockets 15 prevents displacement of the sections, both laterally and longitudinally. In the peculiar "Lackawanna" type of double interlock steel sections having double pockets, in the joints, the grout adds somewhat to the tensile strength of the joint and greatly to the lateral strength. In this particular type of steel section the joints are practically water tight on account of the three points or lines of contact between the interlocking flanges, even without additional packing, but the grouting insures such water-tightness and in other forms of steel sections, that may be used, is of great importance to that end.

As particularly illustrated in Figs. 5 and 6, the concrete terminates a short distance above the lower ends of the steel sections and is beveled as shown at 16. The projecting steel end 17 acts as a cutting edge and the bevels promote easy driving.

Preferably the concrete terminates a short distance below the upper end of the steel section leaving the short projecting end 18 to receive the blows of the pile driver, whereby the injury to the cement is avoided. The end 18 has one or more holes 19 for handling the sections. When the wall or a sufficient part of the wall is completed by the driving of enough sections, a finishing top, or coping 21 of concrete, or other plastic material, is added to cover and protect the upper ends of the steel sections.

In Fig. 7 is indicated a section with concrete applied to the lower portion only, desirable for driving in water with the naked upper end of the steel core projecting above.

5 When a series have been driven, long rods may be inserted through the ribs on several steel sections and the concrete applied to the wall as a whole or to a large section of the wall. The rods may be staggered as indicated in the upper portion of Fig. 5.

10 While the securing rods as shown are desirable means for securing the concrete to the steel wall, yet other projections or additions to the ribs may be used for instance 15 channels 25 riveted in place, as shown in Fig. 8 or the angles 26 of Fig. 13.

I have thus produced an interlocking composite sheet piling that gives essentially new results under the pile-driver.

20 More fully to explain my invention and to illustrate the new uses to which my new composite piling is applicable, (where heretofore wood piling, mattresses, rip-rap, etc. only could be used and where ordinary reinforced 25 concrete structures were absolutely impracticable) I have illustrated a few permanent structures to show the various principles involved.

In Fig. 9 are shown a series of inclined 30 baffle walls 30, strengthened by lateral walls 31 and arranged to prevent shore or bank erosion. Such a structure is particularly adapted to save expense for much less wall per unit of shore line is required than where 35 a continuous wall is used.

In Fig. 10 is illustrated the use of my peculiar composite piling to form a series 40 of pockets 33 adapted to be filled with sand, stone, broken rock or any heavy local material. The width of the wall 34, the size of the pockets and the height are controlled by local conditions, to give stability. The depth 45 of penetration of the sections of course must also be proportioned to the strains and loads.

45 In Fig. 11 is illustrated a suitable construction of corner in which one of the steel core sections 37 is made continuous and two half sections 38 are secured to the center of its web by angles 39. Two or more rods 40 50 or other projections are secured to the webs of the steel sections to bind in position the cement 41 surrounding and protecting this central portion, and leaving a large interlocking grouting pocket 42 between this central portion, or pillar, and the ends of the walls extending in the four directions. 45 55 60 are buttresses in which the cement is bound in position by a special arrangement of securing rods 46. On the outer ends of the 65 buttresses wooden fenders 48 are secured in place by bolts 49 having enlarged ball ends 50 to engage with the groove in the end of the steel section.

As bearing piles are used in structures 70 which are for the most part permanent and

as my peculiar sections are formed and protected, so as to be particularly adapted to permanent work, therefore they can be used as bearing piles as well as for sheet piling, whereas interlocking steel piling, the basis of my invention has heretofore been adapted only for sheet piling and in temporary work and not for bearing piles.

70 Fig. 12 illustrates a structure in which my peculiar composite sections are used both 75 as sheet piles and as bearing piles. There is here shown a series of circular walls 50 forming pockets to be filled with stone, gravel etc. inclosed in straight walls 51 and particularly adapted for docks with super- 80 structures etc. Here my peculiar sections act as bearing piles in reference to the load of the superstructure, but as sheet piling in reference to excluding the water and retaining the filled material. In this figure is illustrated 85 the angular arrangement of the slabs for which they must be particularly formed, with the cement facing on one side narrower than on the other and the edges inclined to fit as nearly as may be.

90 While I prefer the "Lackawanna" type of steel sheet piling with which to construct my peculiar composite sections yet other forms of steel sheet piling may be used, and as an illustration I have shown in Fig. 13, 95 such a form having a ball 63 and large flanges 64 along one edge and smaller flanges 65 along the other edge of each steel section.

Fig. 14 shows a particularly strong form 100 of steel sheet piling adapted to be used as a core herein and for other purposes because it approximates the section of a circular column, so far as strength is concerned. This form has a web with interlocking 105 flanges along both edges and two continuous reinforcing flanges extending outwardly from the body of the web on each side; this is not merely a duplication of the flanges, but is an approximation to a circular column as indicated and produces a sheet piling capable 110 of resisting a great amount of strain both vertically and laterally, in proportion to its weight. I am aware that this form is difficult to be rolled integrally with the size of rolls now in use, but it may be fabricated, 115 though as aforesaid I prefer to roll my steel cores in a single piece.

120 Though generally speaking the concrete will be secured on both sides of the slabs, or steel sections yet, if desired, it may be applied to one side of the steel only, as shown in Fig. 3.

125 While I prefer the form of slab sections here shown, yet the steel sections, forming the core of the wall, may first be driven in place and the concrete applied thereto after they are in position and to one or both sides.

Having thus described my invention, what I claim is,—

130 1. As a new article of manufacture, a

- composite piling slab adapted for permanent use consisting of a steel core and of concrete applied to both surfaces of said core, said core being provided with interlocking members along both edges to interlock with corresponding members on the cores of adjacent slabs and also provided with ribs on the web of the core section and with binding projections on the ribs for the concrete.
2. As a new article of manufacture, a composite piling slab adapted for permanent use consisting of at least one steel core section and of concrete applied to the surface of the core, said core being provided with interlocking members along both edges to interlock with corresponding members on the cores of adjacent slabs and also provided with ribs on the web of the core section and with rods inserted through holes in the ribs for binding the concrete.
3. As a new article of manufacture, a composite piling slab consisting of a steel core and of a protecting concrete facing applied to the surface of the core, said core being provided with interlocking members along both edges to interlock with corresponding members on the cores of adjacent slabs and also provided with ribs on the web of the core section and with binding projections on the ribs for the concrete, the steel core projecting as a cutting edge at the lower end below the concrete and the lower portion of the concrete adjacent to the steel lower end being beveled.
4. As a new article of manufacture, a composite piling slab consisting of a steel core and of a protecting concrete coating applied to the surface of the core, said core being provided with interlocking members along both edges to interlock with corresponding members on the cores of adjacent slabs and also provided with ribs on the web of the core section and with binding projections on the ribs for the concrete, the upper end of the core being unprotected by concrete and being adapted to receive a concrete coating on the face and at the top after a plurality of slabs have been installed, substantially as shown.
5. As a new article of manufacture, a composite piling slab adapted for permanent use consisting of a steel core of steel sheet piling and of a concrete coating applied to both surfaces of the core, said core being provided with interlocking members along both edges to interlock with corresponding members on the cores of adjacent slabs and also provided with ribs on the web of the core section and with binding projections on the ribs for the concrete, said core projecting at the lower end beyond the concrete and the concrete on both sides adjacent to said lower end being beveled for easy driving and the core at the upper end
- projecting beyond the concrete and being provided with at least one hole for engagement of the handling means, substantially as described and shown.
6. As a new article of manufacture a wall composed of composite piling slabs adapted for permanent use, each slab consisting of a plurality of steel core sections and of concrete applied to both surfaces of the core, said core being provided with interlocking members along both edges to interlock with corresponding members on the cores of adjacent slabs and also provided with ribs on the web of the core section and with rods inserted through ribs on a plurality of sections for binding the concrete, substantially as described and shown.
7. As a new article of manufacture, a structure composed of composite piling slabs inserted in the earth, said slabs being adapted for permanent use and consisting of steel core sections and of concrete applied to both surfaces of the core, said core being provided with interlocking members along both edges to interlock with corresponding members on the cores of adjacent slabs and also provided with ribs on the web of the core section and with rods inserted through holes in the ribs of a plurality of sections for binding the concrete, said rods being staggered.
8. A structure composed of a series of interlocking steel sheet piling sections, and of a coating of cement applied to the surface of the sections, each section being provided with at least one longitudinally extending rib on its web and with projections on the web for binding the cement to the sections.
9. As a new article of manufacture, a structure composed of composite piling slabs driven into the earth substantially vertically, each slab consisting of a steel core and of concrete applied to both surfaces of said core, said core being provided with interlocking members along both edges to interlock with corresponding members on the cores of adjacent slabs and also provided with ribs on the web of the core section and with binding projections on the ribs for the concrete, the edges of the slabs being recessed from end to end forming pockets in the wall and said pockets being filled with grout.
10. A structure composed of composite piling slabs each slab consisting of a steel core and of concrete applied to both surfaces of said core, said core being provided with interlocking flanges along both edges to interlock with corresponding members on the cores of adjacent slabs, said flanges being formed to provide joint pockets, and the edges of the slabs being recessed to form pockets on both sides of the core, and said joint pockets and edge pockets being filled with grout.

11. A structure composed of composite piling slabs, each slab consisting of a steel core and of concrete applied to the surface of the core, said core being provided with 5 interlocking members along both edges to interlock with corresponding members on the cores of adjacent slabs and also provided with ribs on the web of the core section and with binding projections on the ribs for the 10 concrete, said slabs being arranged to form lateral walls and reinforcing walls therefor.

12. A structure composed of composite piling slabs, each slab consisting of a steel core and of concrete applied to the surface 15 of said core, said core being provided with interlocking members along both edges to interlock with members of the core of adjacent slabs, said slabs being arranged to form lateral walls and angular walls and 20 buttresses provided with fender faces, said angular walls being connected to the lateral walls and the buttresses being connected to the walls by the engagement of the interlocking members on the slab cores.

13. As a new article of manufacture, a composite piling slab consisting of at least one steel core section and of concrete applied to the surface of the core, said core being provided with interlocking members along 30 both edges to interlock with corresponding members on the cores of adjacent slabs and also provided with ribs on the web of the core section and with rods inserted through holes in the ribs for binding the concrete, 35 said rods being bent to extend outwardly beyond the ribs and having their ends bent back to engage with the section web.

14. In a structure composed of composite piling slabs, a central member for forming a joint between intersecting walls, said member consisting of a steel sheet piling section, two half sections secured to the web of the first section by angle irons and extending 40 outwardly from opposite sides of said web substantially at a right angle, said section and half sections being provided with interlocking flanges on their edges, a series of binding wires for the concrete inserted through the section webs and having bent 45 ends and concrete applied to said sections and forming therewith a composite pillar.

15. As a new article of manufacture, a composite piling section consisting of a steel core and of concrete facing applied to the 50 surfaces of the core said core being provided with binding projections at both sides to bind the concrete in position and of interlocking members along both edges, said members projecting beyond the edges of the concrete facing sufficiently to engage with 55 similar members on the cores of adjacent sections.

16. As a new article of manufacture, a composite piling section consisting of a steel core and of a protective concrete coating 60

applied to both surfaces of the core, said core consisting of one or more sections of interlocking steel sheet piling having interlocking members along both edges of each section to interlock with corresponding members on adjacent sections and the outer interlocking members of each core extending beyond the edges of the concrete facing to interlock with similar members on adjacent cores and said sections also being provided with integral binding projections on the sections to engage with and firmly bind the concrete facing in position on the core. 70

17. As a new article of manufacture, a composite piling section, consisting of a steel core having interlocking members along its edges, to interlock with corresponding members on the cores of adjacent slabs, and of concrete applied to the surfaces of the core, said core being provided with 85 projections on its web to engage with and bind the concrete securely to the core to form a unitary article. 88

18. A continuous tight wall composed of composite piling sections each section consisting of a steel core and of concrete facing applied to the surfaces of the core said core being provided with binding projections on its web at both sides to bind the concrete in position and with interlocking members 90 along both edges, said members projecting beyond the edges of the concrete facing, sufficiently to engage with similar members on the cores of adjacent sections. 95

19. A continuous tight wall composed of composite piling sections driven adjacent, said sections consisting each of a wall core and of concrete facing applied to the surfaces of the core said core being provided with binding projections on its web to extend 100 on both sides into engagement with the concrete for binding the same in position and with interlocking members along both edges said members projecting beyond the edges of the concrete facing to engage with 105 similar members on the cores of adjacent sections and the spaces between the edges of the composite sections being filled with a concrete material. 110

20. As a new article of manufacture, a structure composed of composite piling slabs inserted in the earth, said slabs being adapted for permanent use and consisting of steel core sections and of concrete applied to both 115 surfaces of the core, said core being provided with interlocking members along both edges to interlock with corresponding members on the cores of adjacent slabs and also provided with projections on both sides of the web of the core section to engage with 120 and firmly bind the concrete facing in position on the interlocking sections. 125

21. As a new article of manufacture a wall composed of composite piling slabs adapted for permanent use each slab con- 130

sisting of one or more steel core sections and of concrete applied to both surfaces of the core, said core being provided with interlocking members along both edges, extending beyond the edges of the concrete to interlock with corresponding members on the cores of adjacent slabs and also provided with binding projections to bind with and secure the concrete facing firmly in place,

said core projecting at both its lower and its upper ends beyond the concrete.

In testimony whereof I have signed my name to this specification in the presence of two subscribing witnesses.

CLOUD CLIFFORD CONKLING.
